UNITED STATES PATENT OFFICE.

WILLIAM JOHNSTONE, OF OTTAWA, ONTARIO, CANADA.

STEAM-BOILER.

SPECIFICATION forming part of Letters Patent No. 247,920, dated October 4, 1881.

Application filed July 22, 1881. (No model.) Patented in Canada May 26, 1880.

To all whom it may concern:

Be it known that I, WILLIAM JOHNSTONE, of Ottawa, in the county of Carleton and Province of Ontario, Canada, have invented a new 5 and Improved Steam-Boiler, of which the following is a specification.

The object of this invention is to provide a cheap and efficient boiler for generating steam for mechanical purposes, for heating dwellings, 10 and other purposes; and the invention consists of a boiler or steam-generator having a water-chamber with drop-tubes forming the top of the boiler, which top is connected by vertical tubes to an annular chamber forming the base 15 of the boiler. The fuel-entrance is obtained by shortening the required number of tubes from top and bottom, and the grate-bars are within the circumference of the annular base.

In the accompanying drawings, Figure 1 is 20 an elevation of my improved boiler with the front of the casing or jacket removed, and also some of the tubes, in order to exhibit other parts. Fig. 2 is a vertical sectional elevation of the same, with parts removed to exhibit other 25 parts. Fig. 3 is a cross-section of the boiler on line *y y*, Fig. 1. Fig. 4 is a cross-section of the boiler on the line *x x*, Fig. 1.

Similar letters of reference indicate corresponding parts.

30 In the drawings, *A* represents the cylindrical upper section or chamber of the boiler for containing water and steam, from which chamber *A*, and communicating therewith, drop-tubes *B*, for containing water, depend into the fire-chamber *C*.

The tubes *B* gradually increase in length from the center of the said chamber *A* outward to the row of circulating-tubes *E*, and the longest ones of which extend a little more 40 than half-way the distance between the said chamber and the grate, as shown in Fig. 2.

45 *E* represent water-circulating tubes extending from near the circumference of the upper chamber, *A*, into the annular chamber *D*, that forms the base of the boiler, said tubes *E* thereby forming the exterior wall of the boiler.

Within the circumference of the chamber or base *D* is fixed the grate *F*, pivoted on a cross-bar, *G*, or other suitable device, to allow 50 said grate *F* to be shaken to clear the fire. The ashes from the fire are designed to fall into the pit *H*.

The fuel is introduced into the fire-chamber 55 *C* through an opening, *I*, which is formed by

substituting for several tubes *E* tubes *K*, depending from the chamber *A* for about one-half the depth of the boiler, and by inserting in the chamber *D* corresponding tubes *L*, that extend upward a short distance and have their 60 upper ends connected by a horizontal curved cross-tube, *M*, with tubes *E*, as shown. These outer tubes, *E E*, are in close contact with the fire, forming the exterior of the boiler, and cause a water-circulation through the chambers *A D*. 65

The drop-tubes *B K*, being closed at their lower ends, cause ebullition in the chamber *A*, and the said tubes are set far enough apart for the products of combustion to circulate freely 70 between them.

N represents the casing or jacket of the boiler, of cylindrical shape and constructed of iron or brick, as may be desired, being of brick in this case. Said casing or jacket *N* is 75 enlarged at the top about the tops of the tubes *E E* and chamber *A*, thereby forming an annular flue, as shown at *O*, completely inclosing said chamber *A*, and causing the products of combustion from the fire-chamber *C* to circulate about it, passing horizontally between the tubes, and thence vertically up the sides of the chamber *A* and over its top, as indicated by arrows, Fig. 2. 80

The sides of the jacket or casing *N* are carried up above the chamber *A* and covered by a plate, *P*, from the center of which extends the smoke-pipe *Q*.

R represents the feed-water pipe for conducting water to the chamber *D*, and *S* represents the pipe for carrying off the steam or hot water.

Having thus fully described my invention, I claim as new and desire to secure by Letters Patent—

In a steam-boiler, the combination, with the cylindrical chamber *A*, arranged above the fire-chamber, and the annular chamber *D*, surrounding the grate, of the drop-tubes *B K*, the connecting-tubes *E*, the short tubes *L*, and the horizontal pipe *M*, substantially as and for the purpose set forth.

The above specification of my improvement in boilers for generating steam or heating water signed by me this 5th day of July, 105 1881.

WILLIAM JOHNSTONE.
